[57] CLAIM

The ornamental design for a vehicle soft top, as shown and described.

DESCRIPTION

FIG. 1 is a perspective view of a vehicle soft top showing our new design, the vehicle body shown in broken lines is for illustrative purposes only and forms no part of the claimed design.

FIG. 2 is an enlarged side elevational view thereof, the opposite side being substantially a mirror image of that shown.

FIG. 3 is an enlarged top plan view thereof.

FIG. 4 is an enlarged bottom plan view thereof.

FIG. 5 is an enlarged front elevational view thereof.

FIG. 6 is an enlarged rear elevational view thereof.
